SAFETY RAZOR

Axel S. Carlson, New York, N. Y., assignor, by
mesne assignments, of one-half to J. Curtis
Blue, Brooklyn, N. Y.

Application May 1, 1935, Serial No. 19,256

17 Claims. (Cl. 30—60)

My present invention relates to a type of safety razor in which a double edged razor blade is mounted on a supporting plate and is held in tight clamped relation to the supporting plate by 5 a clamping plate, this clamping plate being hinged to one end of the supporting plate and moving in an arcuate path from an open position to a closed position.

My invention may be considered as an improvement or further development of my Safety razor holder, Serial No. 748,371 filed October 15, 1934, matured to Patent No. 2,024,626 issued December 17, 1934 and also of my application for Safety razor, Serial No. 754,969, filed November 27, 1934, 15 matured to Patent No. 2,064,884, issued December 22, 1936.

One of the main objects and features of my present invention is in the razor blade itself, this being a double edged blade with the edges parallel, but having the central section of the blade rather thin so that the blade may be bent into an arc considered transversely of the blade. Therefore by my construction of the flexible razor blade, the opposite edge portions of the blade 25 adjacent the cutting edges are formed of a relatively thick section of metal, thus giving sufficient rigidity to the cutting edges and providing material which may be ground down and resharpened to give renewed cutting edges. The thin central section of the blade facilitates the ready bending or flexing of the blade into an arc.

Another object and feature of my invention is constructing the supporting plate and the clamping plate of a desired shape and cross section so 30 that the blade may be bent in the desired arc and held clamped for shaving. In general configuration the upper surface of the clamping plate is convex in transverse curvature. However, by my construction the edge portions of the clamping 35 plate are at a tangent to the convex portion of the curve where the flexible part of the blade is bent. Therefore the stiffened thick edges of the blade rest on flat surfaces of the clamping plate and not on a curve, and the thick portions adjacent the edges of the blade do not need to flex.

The clamping plate is constructed somewhat V-shaped in transverse cross section, the V angle however, being a broad obtuse angle. This may be curved at the point of the V with a concave 40 curvature to conform with the convex curvature of the supporting plate where the flexible section of the blade is clamped between the supporting and clamping plate. This convex curved section also gives a clearance above the blade. The marginal edge portions of the clamping plate are

plane and parallel to the tangential sections of the supporting plate, so that the thickened edges of the blade are effectively clamped between two plane surfaces. This construction presents the two edges of the blade in a better position for 5 shaving than in safety razors in which a flat double edge blade is used or in which a thin double edge blade is bent in an arc of a circle.

Another object and feature of my present invention is forming a hinged mounting and support for the clamping plate so that when such plate is parallel to the supporting plate, it may be moved in a longitudinal direction, this being for the purpose of allowing insertion of the blade on the clamping plate with the blade in a flattened 10 position, such blade normally being flat unless bent by the holding parts of the safety razor. Thus when the clamping plate is moved axially parallel to the supporting plate, the outside edges of the clamping plate engage the thickened portions of the razor blade, bend the blade into an 15 arc and hold the blade securely to the supporting plate. This arrangement uses a spring to permit the parallel movement of the clamping plate relative to the supporting plate.

Another object and feature of my present invention is in the construction and manner of manipulating a stem operating in a handle and having a head to engage the clamping plate, such stem being rotatable on its axis and also movable 20 longitudinally. In the present arrangement I form a guide sleeve with a Z-shaped slot. This slot therefore has a central portion transverse to the sleeve and two end arms extending longitudinally of the sleeve so that the pin which is rigidly 25 connected to the stem may operate in two longitudinal portions and also in the cross portion of the slot and thus better accommodate the parallel movement of the clamping plate in reference to the supporting plate.

Another feature of my invention consists in the employment of a pilot pin resiliently supported by a spring in the supporting plate and having a head extending through a slot in the blade, which head engages in a centering recess 40 in the clamping plate and thus counteracts or equalizes the action of the spring in the hinged arms of the clamping plate during the parallel motion of the clamping plate towards and from the supporting plate, which motion is caused by 45 the head on the stem. My invention may also be considered as a further development of that of my application Serial No. 705,081, filed January 3, 1934, for Hinged clamp safety razor holder, matured into patent dated July 23, 1935, Patent 55

No. 2,008,681, as it relates to the rotation of the stem and the pivoting of the clamping plate.

My invention is illustrated in connection with the accompanying drawings, in which,

5 Fig. 1 is an elevation taken in the direction of the arrow 1 of Fig. 3, the handle being illustrated in section and the blade gripped between the supporting and clamping plates.

Fig. 2 is an elevation similar to Fig. 1 with the clamping plate in its open position and the blade flattened.

Fig. 3 is an end elevation taken in the direction of the arrow 3 of Fig. 1.

Fig. 4 is an enlarged vertical section taken on the line 4—4 of Fig. 3, the handle and the operating mechanism for the stem being shown in section, with the clamping plate in open position.

Fig. 5 may be considered as a transverse section on the line 5-5 of Fig. 1 in the direction of the arrows, prior to lowering the clamping plate to flex the blade and with the razor blade shown flat.

Fig. 6 is a plan of the blade.
25 My invention as it relates to the blade is as follows: Having reference particularly to Figs. 4, 5 and 6, the blade as a whole is indicated by the numeral 11. This has a thin central plate or web section 12 with an elongated slot 13 therein
30 and two marginal centering slots 14. At each end there are guide tabs 15 which may be used for finger grip ends to place the blade on the supporting plate properly centered and to remove it therefrom. The termination of the
35 blade proper is at the ends 16 and the tabs form shoulders 17 therewith.

The blade has two thickened marginal portions 18 sharpened on opposite edges 19. These thickened sections are sufficiently stiff so that they do not bend or flex when the blade is bent transversely. They also have sufficient rigidity to resist longitudinal flexing of the edge of the blade. Therefore under all conditions of gripping and clamping the blade between the supporting and clamping plates, each cutting edge forms a straight line; the cutting edges being parallel provided the blade is correctly ground. The center or web portion is of sufficient thinness so that the blade may readily be bent transversely. The thickened portion 18 of the blades also provides a considerable body of metal to allow regrinding and resharpening of the blades a number of times.

In my invention the blade holder designated by the assembly numeral 25, employs a supporting plate 26. This as illustrated in Fig. 5, preferably has a flat undersurface 27, but if desired this may be made thinner at the center for sake of lightness. The central portion considered transversely has a convex curvature 28 adjacent the marginal edges. The surface 29 is tangential to the convex curve 28. These opposite surfaces on the top adjacent the marginal edges thus form plane surfaces. A series of transverse ribs 30 project slightly above the main surface of the clamping plate and at each end there are shoulders 31 of the same height as the ribs and fingers 32 extend upwardly at each side of the shoulders 31, these having a space to accommodate the tabs 15 so that the upper ends of the fingers 32 fit between the ends 16 of the blades and the side shoulders 17 of the tabs 15 on the blade. The clamping plate at its mid position has a pair of slight bosses 33 which are slightly

higher than the ribs to engage in the guide slots 14 of the blade when the blade is flexed.

The supporting plate at its marginal edges has guard teeth 34, thus forming a comb like structure of the usual character to extend beyond the cutting edge of the blade when the blade is flexed. At the central portion of the supporting plate adjacent one end, there is a perforation 35 with a socket 36 below the perforation and a socket 37 above the perforation leading to the top surface of the blade. Slidably mounted in this perforation there is a pilot pin 38, such pin having a head 39 at the top and being upwardly pressed by a spring 40. This spring seats in the bottom of the upper socket 37 and the underside of the head 39, tending to thrust the pilot pin upwardly. The upward displacement is limited by the button 41 secured to the lower end of the pilot pin and operating in the lower socket 36. The head 39 is less in diameter than the slot 13 of the plate so that it may extend through this slot. A tubular handle 45 is secured to the underside of the supporting plate and if desired may be made integral with such plate. This handle has internal screw threads 46 at its lower end, of a fine pitch, to which is threaded an end plug 47 this having a knurled end 48 to provide a finger grip. A guide sleeve 49 is secured adjacent the upper portion of the tubular handle, this sleeve having a guide slot 50 therein, formed Z-shape. This slot thus has a transverse section 51 transverse to the axis of the sleeve, a lower and an upper longitudinal slot section 52 and 53, these being parallel to the axis of the sleeve.

At the upper end of the handle there is a 35 guide slot 54 and opposite thereto a second slot 55 extending to a slightly greater extent longitudinally of the handle from the underside of the clamping plate. Both of these slots preferably have parallel edges 56 parallel to the axis 40 of the handle and a transverse flat bottom edge 57 (note Fig. 5).

The hinge or pivot connection of the clamping plate to the supporting plate designated by the assembly numeral 60, is as follows: A pair of ears 61 depend from one end of the supporting plate and in these ears there is mounted a rotatable pintle shaft 62 which shaft carries a pinion gear 63. This shaft is squared at its ends and each end carries a short arm 64 and each arm has mounted on its end a tubular housing 65. This housing has an enlarged lower end 66 (note Fig. 4) with a base 67 and reduced upper end 68. Rods 69 are slidably mounted in the upper end of the tubes and each rod has a head 70 at the bottom against which operates a compression spring 71, this spring bearing on the bottom 67. This gives a resilient mounting for the rods 69 which rods are connected at their outer ends to the clamping plate 75. This plate has a thin central section 76 convex on its upper surface and concave on its lower surface with thickened side portions 77. Each of these side portions has its undersurface forming a flat plane so that when the clamping plate is turned over the supporting plate in the position of Fig. 5, the underside of the ends 77 will be parallel to the upper surface of the ribs on the supporting plate. In other words, the surface 29 of the supporting plate and the undersurfaces of the side parts 77 are in parallel planes 78 when the device is in the position of Fig. 5 and when they are clamped in the position of Fig. 3. The clamping plate has an extension 79 at one end to which the rods 69 are connected, this extension fitting between the fingers 32. The 75

clamping plate has an extension 79 at its opposite end, fitting between the fingers at the remote end of the supporting plate. There are a series of projecting teeth 80 on the marginal edge of the 5 clamping plate bearing on the thickened portions 18 of the razor blade.

The clamping plate is rotated on its hinge pindle by means of a rack bar 85. This may operate in guides on the underside of the supporting 10 plate if desired, as shown in certain of my former patents, or it may be guided by having the enlarged end 86 operating in the slot 55 on one side of the handle and the main portion of the rack bar 87 operating in the slot 54. Moreover, the 15 rack teeth 88 engaging the pinion holds the rack bar in proper operative position.

The rack bar has a hollow space 89 in which operates a plunger 90 having a stem 91, the stem being guided in the socket 92 in the rack bar and 20 the plunger pressed inwardly towards the handle by a compression spring 93, this construction being similar to that of my patent application Serial No. 754,969 above mentioned. In this case I use a wedge block 95 of a type similar to that of this 25 patent application, mounted and operating in the same manner on a longitudinally movable and rotatable stem 96. The head 97 of the stem operates through a slot 98 in the clamping plate. The clamping plate also has a slight recess 99 to 30 engage the head 39 of the pilot pin 38. In this case however, the pin 100 secured to the stem operates in a Z-shaped slot 50 and thus this pin may move in the transverse portion 51 of the slot or the parallel opposite end portions 52 and 35 53. The end of the stem is threaded into the plug 47 in the same manner as in my patent application No. 754,969 just mentioned.

The manner of operation and function of my 40 invention is substantially as follows: The clamping plate may be turned on its hinge by manipulation of the end plug 47 which has a fine threaded connection with the tubular handle and a coarse threaded connection with the stem. This adjustment is in a manner similar to that of my 45 patent application Serial No. 754,969, for Safety razor, filed November 27, 1934, matured to Patent No. 2,064,884 issued December 22, 1936. This action may be used to both open or close the clamping plate relative to the supporting plate. 50 The action also gives a longitudinal movement to the stem and the head of the stem when the pin 100 operates in the longitudinally extending portions 52 and 53 of the slot 50 in the fixed guide sleeve 49. When the pin moves in the 55 horizontal part 51 of the slot 50, the stem is rotated one-quarter of a turn to rotate the head so that it may pass through the slot 98 in the clamping plate and also so that such head may give a downward pull on the clamping plate when it is 60 parallel to the supporting plate.

The razor blade when inserted on the clamping plate with the supporting plate in its open position is flat as shown in Fig. 5. The tabs 15 of this blade fit between the fingers 32 on the supporting plate and thus properly center the blade. 65 The stem also extends through the central slot 13 of the blade. After the clamping plate has been turned on its hinge into a position parallel to the supporting plate, the two edges of the 70 clamping plate engage the thickened section of the marginal portions of the blade as shown in Fig. 5. During this action of hinging or turning, the clamping plate from its open to its closed position, the stem is drawn downwardly with the 75 measurement of the head extending lengthwise

of the clamping plate through the slot 98. In this action the pin 100 operates in the section 53 of the slot 50. The further manipulation of the plug 47 forces the pin 100 to follow the transverse section 51 of the slot 50, which action rotates the stem and the head of the stem one-quarter of a turn, bringing the long measurement of the head transverse to the slot 98.

When the clamping plate is rotated on its hinge, the rods 69 are thrust outwardly by the 10 spring 71. This holds the clamping plate elevated above the supporting plate. The pilot pin 38 has been thrust upwardly by the spring 40 so that its head 39 extends through the slot 13 of the blade and engages in the recess 99 on the underside of the clamping plate. The further downward movement and pull exerted on the stem when the pin 100 operates in the longitudinal portion 52 of the slot 50, draws the clamping plate downwardly towards the supporting plate with a parallel motion, the rods 69 cause a compression of the springs 71 and at the same time the spring 40 which gives a resilient pressure to the pilot pin is also compressed. These two sets of springs, one at the hinge and the other towards 15 the opposite end of the supporting plate, give a substantially even resistance to the approach of the clamping plate towards the supporting plate. This approach movement causes a flexing of the 20 thin or web section 12 of the blade and causes the slight bosses 33 on the supporting plate to extend through the slots 14 in the web portion of the blade. This prevents the blade from having any 25 slight twist. The clamping plate is pulled down tightly on the blade, causing a firm gripping of 30 the thickened edge portions 18 of the blade between the supporting plate at the bottom and the clamping plate at the top. This gripping action is shown in Fig. 3, the marginal portions of the 35 blade being shown dotted.

As above mentioned, the portions of the supporting plate and clamping plate which engage the thickened sections of the blade are in effect 40 plane surfaces, or edges and thus there is no tendency to bend or flex the thickened sections of 45 the blade, but these are held in a vice-like grip from one end of each cutting portion of the blade to the other end, and thus press the cutting edges in an inclined position in reference to the handle when the blade is in position for shaving.

It will be noted by reference to the drawings, that the transverse ribs 30 which support the blade and the thickened marginal portions 18 thereof, have their upper surface not only spaced above the upper surface of the supporting plate 55 26, but above the upper surface of the marginal guard teeth 34. This therefore supports the cutting edge of the blades and thickened portion 18 well above the guard teeth, which construction facilitates the cleansing of the assembled 60 razor with the blade by forcibly pouring water over the assembled structure with the clamping plate holding the blade in tight clamped relation to the supporting plate.

Various changes may be made in the details 65 of construction without departing from the spirit or scope of the invention as defined by the appended claims.

I claim:

1. In a safety razor, the combination of a supporting plate, a clamping plate hinged thereto, the supporting plate having means for mounting and centering a razor blade, means to move the clamping plate when in a position parallel to the supporting plate in a clamping relation towards 75

the supporting plate, the hinge connection between the clamping and the supporting plates having means to permit such parallel motion, a resiliently mounted pilot pin interengaging between the supporting and clamping plates when in parallel relation, the said pilot pin being movable when the clamping plate is brought into clamping relation with the supporting plate.

2. In a safety razor, the combination of a tubular handle having a supporting plate at one end, a longitudinally movable and rotatable stem mounted in the handle and extending through the supporting plate, the stem having an elongated head, the supporting plate having means to engage and center a razor blade, a clamping plate hinged to the supporting plate at one end thereof and adapted to swing in an arc and to first occupy a position parallel to the supporting plate but spaced therefrom, the stem having a pin, a structure having a slot with the pin engaging therein, said slot having a transverse portion normal to the stem and two marginal end portions parallel to the stem extending in opposite directions from the central portion of the slot said clamping plate having a perforation for passage of the head of the stem whereby a movement of said pin in said slot rotates the head and moves it axially of the handle to engage and move the clamping plate.

3. In a safety razor as claimed in claim 2, the hinged connection of the clamping plate to the supporting plate having a resilient mounting at the hinge, said mounting normally holding the clamping plate spaced from the supporting plate when they are in parallel position, the said resilient mounting being adapted to permit movement of the clamping plate from a spaced to a clamping relation with the supporting plate.

4. In a safety razor as claimed in claim 2, the hinged connection of the clamping plate to the supporting plate including rods connected to the clamping plate and connected to the hinge by a spring mounting, the said spring mounting being adapted to support the clamping plate parallel to and in spaced relation from the supporting plate, a pilot pin having a contact end, a spring to normally elevate the contact end of the pilot pin, said contact end being adapted to engage the clamping plate remote from the hinge and to hold the remote end of the clamping plate spaced from the supporting plate, the clamping plate having a perforation, the stem being adapted to extend through said perforation when the clamping and supporting plates are in parallel position, the inter-engaging means between the hinge and the stem operating the stem to first develop a longitudinal movement of the stem, means actuated by the first longitudinal movement of the stem to rotate the clamping plate on its hinge from its open to its parallel spaced position relative to the supporting plate, means operative in the further actuation of the stem to rotate the stem and to then move the head of the stem towards the supporting plate to shift the clamping plate from its spaced to its clamping relation to the supporting plate.

5. In a safety razor, the combination of a supporting plate having ribs transverse thereto, the said ribs at the central portion being curved in an arc and at their marginal edges being tangential to the arc, a clamping plate, means to support said plate in spaced and parallel relation to the supporting plate, the marginal undersurfaces of the clamping plate being parallel to the tangential portions of the ribs, means to support and

center a flat razor blade on the ribs of the supporting plate, means to move the clamping plate from a spaced to a clamping relation with the supporting plate, whereby the clamping plate bends the blade with the center portion arched in a curve and its marginal portions held against the tangential portions of the ribs, the blade having a thin central web section of constant thickness and marginal thickened sections, the thickened sections having parallel cutting edges, the central section being provided with a portion of the means for centering the blade on the supporting plate, the said blade being normally flat, the marginal edges of the clamping plate engaging the thickened sections of the blade in both the spaced and the clamping relation to the supporting plate.

6. In a safety razor as claimed in claim 5, two resiliently mounted structures interconnecting the supporting and clamping plates, to hold the clamping plate initially in spaced relation to the supporting plate, said mounting being compressible to permit a parallel movement of the clamping plate from its spaced to its clamping relation to the supporting plate, one of said resilient structures engaging the plates between their ends.

7. In a safety razor, the combination of a tubular handle having a structure with a guide slot, a portion of said slot being transverse to the axis of the handle and two end portions of the slot being parallel to said axis and extending in opposite directions to the transverse portion, a stem having a pin thereon and a head slidably movable and rotatable in the handle, a supporting plate connected to the handle, a clamping plate to be engaged by the head, and means operatively connected to the handle to manipulate the stem to cause the pin to travel first in one of the end portions of the slot, then the transverse portion and then the other end portion.

8. In a safety razor, the combination of a supporting plate, a clamping plate hinged thereto at one end, the hinge including a hollow housing with a rod slidable therein, the rod being attached to the hinged end of the clamping plate, a spring in the housing engaging the rod and tensioned to normally press the rod outwardly, whereby when the clamping plate is swung to a position parallel to the supporting plate, the said spring and arm retain the clamping plate in spaced relation to the supporting plate.

9. In a safety razor as claimed in claim 8, a pilot pin resiliently mounted in the supporting plate at a portion remote from the hinge and having a contact end to engage the end of the clamping plate remote from the hinge and to hold such remote end of the clamping plate in spaced relation to the supporting plate, combined with means interconnecting the clamping and supporting plates to move the clamping plate from a spaced to clamping relation to the supporting plate.

10. In a safety razor, the combination of a supporting plate and a clamping plate both having marginal portions forming an obtuse angle to the median line of said plates, means to resiliently position the clamping plate in spaced and parallel relation to the supporting plate, one of said means interengaging the two plates intermediate their ends, means to center a blade between the two plates, and means to move the clamping plate into clamping relation with the supporting plate and thereby flex the blade, said resilient means yielding on such movement of the clamping plate.

11. In a safety razor as claimed in claim 10, the clamping plate being hinged to one end of the supporting plate, the hinge having a pintle and one of the resilient means being adjacent the pintle and having a spring engaging a rod on the clamping plate.

12. In a safety razor as claimed in claim 10, a blade having a central resilient web of constant thickness and two marginal thickened portions 10 each with a cutting edge, the blade having centering slots on opposite sides of the longitudinal center of the blade, the supporting plate having projecting bosses to engage said slots whereby the clamping plate in being moved toward the supporting plate flexes the web portion of the blade 15 and engages the bosses and the slots.

13. In a safety razor, the combination of a handle having a supporting plate centered on the handle, said plate having flat marginal portions 20 forming an obtuse angle with the axis of the handle, a clamping plate having flat marginal portions, means to center the clamping plate in spaced relation to the supporting plate, said flat surfaces of the clamping plate forming an obtuse 25 angle with the axial center of the clamping plate, the supporting plate having projecting bosses on opposite sides of the handle, a blade having a thin, resilient web of constant thickness and two marginal thickened portions each having a cutting 30 edge, the blade having slots to be engaged by said bosses, and means to move the clamping plate from spaced relation to the supporting plate to flex the web in a curved arc and position the thickened marginal portions of the blade between the flat surfaces of the clamping and supporting plates.

14. In a safety razor as claimed in claim 13, the clamping plate being hinged to one end of the supporting plate, such hinge having a pintle, 40 a spring adjacent the pintle, means between the pin and the clamping plate to position the clamping plate spaced from and in parallel relation to the supporting plate, a resiliently mounted pilot pin in the supporting plate engaging the clamping plate remote from the hinge, said spring and pilot pin being displaceable on movement of the clamping plate from its spaced to its clamping relation with the clamping plate.

15. In a safety razor, the combination of a supporting plate having means for mounting and centering a razor blade, a clamping plate hinged to the supporting plate and adapted to permit movement of the clamping plate from a position 45 parallel and spaced from the supporting plate to a position substantially at right angles thereto and for movement of the clamping plate from its spaced parallel relation to the supporting plate in a parallel movement to a clamping position, a

5 pilot pin slidably mounted in the supporting plate, a spring normally elevating one end of the pin above the blade mounted on the supporting plate, the upper end of the pin having means to engage the clamping plate when in its spaced parallel position in regard to the supporting plate, the said pin being compressible when the clamping plate is moved from its spaced position to its clamping position in regard to the supporting plate.

10 16. In a safety razor, the combination of a supporting plate having means for mounting and centering a razor blade, a clamping plate hinged to the supporting plate and adapted to permit movement of the clamping plate from a position 15 parallel and spaced from the supporting plate to a position substantially at right angles thereto and for movement of the clamping plate from its spaced parallel relation to the supporting plate in a parallel movement to a clamping position, a 20 blade mounted between the supporting and clamping plates, said blade having a resilient thin central web of constant thickness and marginal non-resilient thickened portions, each having a cutting edge, the supporting plate having two 25 flat marginal portions at an angle one to the other, the clamping plate having complementary flat marginal portions having a central angle one to the other, the clamping plate being adapted when in spaced relation to the supporting plate, 30 to engage the blade and to flex the web portion of the blade in a transverse curved arc when the clamping plate is moved to its clamping relation with the supporting plate and hold the thickened marginal portions of the blade tangential to the 35 curved arc.

17. In a safety razor, the combination of a supporting plate having a transverse curve on its supporting surface terminating in tangential surfaces adjacent each edge thereof, a clamping 40 plate having an undersurface parallel to the tangential surfaces of the supporting plate adjacent its outer edges, a flat razor blade having a relatively thin flexible web and two non-flexible marginal portions, each of substantially constant 45 thickness with parallel upper and lower surfaces, each thickened portion having a cutting edge, the thickened portions being of substantial width compared with the width of the blade between the cutting edges whereby when the web engages 50 the transverse curve of the supporting surface and the outer portions of the clamping plate engage the thickened portions, a movement of the clamping plate towards the supporting plate flexes the web into an arc and clamps the marginal portions between the tangential surfaces of the supporting and the clamping plate.

AXEL S. CARLSON.
